UNITED STATES PATENT OFFICE.

ERNEST A. EASTMAN, OF DAYTON, OHIO.

CONCRETE-MOLD.

1,202,038.

Specification of Letters Patent. Patented Oct. 24, 1916.

Application filed April 2, 1915. Serial No. 18,726.

To all whom it may concern:

Be it known that I, ERNEST A. EASTMAN, citizen of the United States, residing at Dayton, in the county of Montgomery and State of Ohio, have invented certain new and useful Improvements in Concrete-Molds, of which the following is a specification.

My invention relates to concrete building structures and more particularly to a method 10 of forming hollow walls from concrete or other plastic material and to a collapsible core therefor.

The object of the invention is to provide means for pouring or forming hollow or 15 chambered walls or other bodies of plastic material by a series of courses or stages by means of a removable core which is withdrawn and reset upon each successive course or stage.

20 A further object of the invention is to provide an improved form of collapsible or removable cores adapted to form a hollow or recess having contracted or reduced orifice through which the core may be removed 25 when in collapsed condition, the purpose of such reduced orifice being to form a supporting ledge upon which the core may rest in its superposed position.

With the above primary and other incidental objects in view, as will more fully appear in the specification, the invention consists of the features of construction, the parts and combinations thereof, and the mode or method of operation, or their equivalents, 35 as hereinafter described and set forth in the claims.

Referring to the drawings, Figure 1 is a vertical longitudinal sectional view of a portion of a hollow wall showing different 40 stages of the operation. Fig. 2 is a plan view of the forms and wall shown in Fig. 1.

Fig. 3 is a vertical transverse sectional view of the structure and forms shown in Figs. 1 and 2. Fig. 4 is a detail perspective view 45 of the collapsible core in its distended or adjusted position. Fig. 5 is a top plan view thereof. Fig. 6 is a top plan view showing the extent of the orifice in the finished product and the position of a partially collapsed 50 core in relation therewith. Fig. 7 is a detail perspective view showing the method of setting the form preparatory to pouring the plastic material. Fig. 8 is a detail view of a modification.

55 Like parts are indicated by similar char-

acters of reference throughout the several views.

At the present time it is the custom to construct hollow walls of concrete or other plastic material by means of hollow or chambered blocks laid one upon the other or by means of continuous forms extending throughout the height of the chamber or recess in the structure. The present invention embodies the use of sectional forms which 60 may be withdrawn from the finished portion of the work and used again and again for successive portions or stages. The construction and arrangement is such that at the pouring of each course or stage of the 65 structure a support is provided for the core or form in its succeeding position. Means are likewise provided for connecting the successive recesses or chambers of the structure one with the other in a transverse direction 70 in such way that the chambers will be intercommunicating, permitting a free circulation of air throughout the entire structure.

Referring to the drawings, 1 1 are the side walls or exterior forms as now commonly 75 employed. Located intermediate the side walls in spaced relation both with the side walls 1 1 and in relation one with the other is a series of collapsible cores or interior forms. These cores or interior forms comprise side walls 2 2 divided medially into two 80 sections and hinged one to the other, as at 3. Hinged to each of the side sections 2 is an end section 4 connected thereto at 5. Each core therefore comprises two separable 85 units, each unit consisting of a jointed side wall 2 and an end wall 4 hinged thereto. To facilitate the removal of the sections the corners thereof are rounded, as indicated at 6. The ends of the units are preferably reinforced or faced with metallic plates 7. To 90 facilitate the engagement and disengagement of the sections by permitting the free swinging of the end section 4, said end sections are beveled, as indicated at 8, and the reinforcement plate upon the adjacent 95 rounded corner of the core is extended beyond such beveled portion and overlaps the end section, as indicated at 9. It will be noted that the hinge 5 is so located that the end section 4 swings inward in relation with the core while the hinges 3 are located at the outer side of the side walls 2 whereby the 100 sections of said side walls may be oscillated 105 outward in relation with the core.

Any suitable means may be employed for locking the units in their adjusted or distended position. In the drawings there has been shown a simple form of locking means comprising an angle plate 10 which slidely engages studs or screws 11 upon the end sections and side walls to hold the sections or units of the core connected one to the other. To hold the side walls 2 distended, space blocks 12, as shown in Fig. 7, may be inserted intermediate the walls of the core. The end sections 4 of the core are provided with openings 13 each of which registers with the corresponding opening of the adjacent core. When the cores are set up within the forms, cylindrical plugs or auxiliary forms 14, preferably slightly tapered as indicated in the several figures, are inserted within the openings in the ends of the adjacent cores to form intercommunicating openings in the walls between adjacent recesses or chambers. The top edges of the walls 2 of the unit are beveled as indicated at 15. As before stated, a plurality of these cores are located in spaced relation one with the other and with the side walls 1 of the form and are held in spaced relation by any suitable means. In Fig. 7 of the drawings spaced blocks 16 are shown inserted between the walls of the core and the side walls of the form while recessed bars 17 engage the adjacent ends of succeeding cores.

The collapsible cores, having been properly located within the form and the form having been filled with plastic material to the height of the cores or interior forms, which is allowed to set or partially harden, the cores or interior forms are then collapsed and withdrawn. The first step in the removal of the cores is the disengagement of the auxiliary forms 14 which is accomplished by reaching within one of the hollow cores or forms and pushing or driving the auxiliary core 14 longitudinally into the next succeeding hollow core. The auxiliary forms 14 having been removed, the angle plates 10 are withdrawn thereby disengaging the halves or units of the cores or interior forms one from the other. The end sections of the core or form may then be folded inward into parallel relation with the sides and the joint or medial portion of the side walls may be pulled inward to the angular position shown in Fig. 6. It will be found that the inclined or beveled upper edge of the core or form has produced within the recess or chamber a beveled ledge 18 on the opposite sides of the chamber or recess which contract or restrict the opening of the chamber or recess to a width less than that of the interior dimensions thereof. These lateral ledges or ribs 18, formed by the inclined or beveled edges 15 of the core, constitute supports upon

which the cores are set for the succeeding course. The wall or structure is thus produced in a series of steps or stages each one of a height corresponding to that of the cores and the same cores are used again and again for the successive steps or stages, each time being rested upon the supporting ledge formed by the preceding step or stage. The vertical chambers or recesses formed by the use of the cores in successive positions communicate one with the other through the openings 19 produced by the auxiliary cores 14. In employing the process herein described the builder will provide himself with a sufficient number of collapsible cores or forms to extend in spaced relation once around the structure. This will be found far less expensive than providing special forms or cores corresponding with the height of the structure or wall as is now the case when a monolithic wall or structure is to be produced.

It is obvious that the particular shape and construction of the core or interior form may be modified to meet different conditions of use and the method of locking the same may be changed. An important feature, however, is that of forming at each stage or step of the operation a support upon which the form or core may rest for the succeeding step or stage. It is not essential that the support thus formed shall be continuous throughout the length of the recess or chamber but may consist of a plurality of lugs or projections produced by corresponding recesses or depressions in the form or core, as shown in detail at 20 in Fig. 8, or the recess may be provided with overhanging corners as at 21 in Fig. 8 by correspondingly shaping the cores.

From the above description it will be apparent that there is thus provided a device of the character described possessing the particular features of advantage before enumerated as desirable but which obviously is susceptible of modification in its form, proportion, detail construction, or arrangement of parts without departing from the principle involved or sacrificing any of its advantages.

While in order to comply with the statute the invention has been described in language more or less specific as to certain structural features, it is to be understood that the invention is not limited to any specific details and the construction herein described comprises but one mode of putting the invention into effect and the invention is therefore claimed broadly in any of its possible forms or modifications within the scope of the appended claims.

Having thus described my invention, I claim:

1. In a form for a hollow body formed of plastic material, a removable core including

side and end walls hinged one to another to fold inward upon vertical axes, said core having a top face of less extent than its bottom adapted to produce in the body a recess 5 having a contracted opening upon the margins of which the said core is supported to form a similar recess in the next succeeding course or stage of the body.

2. In a form for a hollow body formed of 10 plastic material, a removable core including side and end walls, the side walls being divided into sections hinged one to the other to fold inward, said core having its upper edges offset in relation with the exterior 15 faces of the walls of the core to produce in said body a recess having overhanging ledges upon which the said core is supported to form a similar recess in the succeeding course or stage of the body.

20 3. A core for a hollow body formed from plastic material comprising a plurality of wall sections arranged in two series, the sections of each series being hinged one to another, and the terminal sections of each series 25 being detachably connected with those of the other series, the external configuration of the core being such that projecting ledges are formed at each molding operation upon which the core is supported during the succeeding molding operation.

4. In a form for a hollow body formed from plastic material, a series of hollow removable cores each having an opening in the wall below the top thereof registering 35 with the corresponding opening of the succeeding core of the series, and a removable auxiliary core engaging the aligned holes of two adjacent cores when in spaced relation, substantially as specified.

40 5. In a form for a hollow body formed from plastic material, a series of cores removable from the recesses formed thereby in the body, and a series of removable auxiliary cores extending intermediate the said 45 first mentioned cores in a mid height position to form intercommunicating openings between adjacent recesses formed by the first mentioned cores.

6. In a form for a hollow body formed 50 from plastic material, a series of spaced hollow removable cores having aligned openings below the top edges of their adjacent sides, and auxiliary cores engaging in said aligned openings in hollow cores and removable 55 therefrom to the interior of the removable hollow cores to form communicating openings in the walls intermediate succeeding recesses formed by the cores.

7. In a form for a hollow body formed 60 from plastic material, a removable core comprising a box like structure, the top face of

which is of less area than the base whereby said core will produce in the body of material a chamber having a contracted orifice, the end and side walls of which are hinged 65 one end wall to each side wall for inward folding, the side walls comprising two sections hinged one to the other for inward folding, and means for connecting the unhinged side and end walls one to another. 70

8. In a form for a hollow body formed from plastic material, a removable core comprising a box like structure open on its opposite sides, the opposite end walls being hinged to the opposite side walls, one end 75 wall to each side wall for inward folding movement, the side walls comprising two sections hinged one to the other to fold outward, holes in the end wall of the structure, and core members to engage in the aligned 80 holes of succeeding core structures.

9. In a form for a hollow body formed from plastic material, a removable core comprising a box like structure, the top face of 85 which is of less area than the base whereby said core will produce in the body of material a chamber having a contracted orifice, the side walls of which are medially flexible and capable of being drawn inward or each toward the other at a mid length point to 90 facilitate the removal of the core from the interior of the hollow body.

10. In a form for a hollow body formed from plastic material, a removable core comprising a box like structure, the side walls 95 of which are medially flexible and capable of being drawn inward or each toward the other at a mid length point to facilitate the removal of the core from the interior of the hollow body, the exterior faces of the sides 100 being contoured to mold ledges on the interior of the hollow body on which the core may be supported during a succeeding molding operation.

11. A form for producing a hollow structure of concrete or other plastic material including an interior form or core comprising a box like structure, the side and end walls of which are foldable inward about vertical axes having its exterior face offset to produce upon the interior face of the recess formed in the structure by said core supporting ledges upon which the form or core may be rested in producing a succeeding course of the structure. 105 110 115

In testimony whereof, I have hereunto set my hand this 27 day of March A. D. 1915.

ERNEST A. EASTMAN.
